UNITED STATES PATENT OFFICE.

JAMES A. GUTHRIE AND HEBER R. WILSON, OF BAR HARBOR, MAINE.

DESIGN FOR A DRILL-BAR.

SPECIFICATION forming part of Design No. 34,484, dated May 7, 1901.

Application filed January 10, 1901. Serial No. 42,807. Term of patent 7 years.

To all whom it may concern:

Be it known that we, JAMES A. GUTHRIE and HEBER R. WILSON, citizens of the United States, residing at Bar Harbor, in the county of Hancock and State of Maine, have invented and produced a new and useful Design for a Drill-Bar; and we do hereby declare the following to be a full, clear, and exact description of the invention, such as will enable others skilled in the art to which it appertains to make and use the same.

In the drawings, Figure 1 is a side view of the drill-bar. Fig. 2 is an end view of the same.

As shown in the drawings, the leading or material features of the design consist of a plain cylindrical bar A, a cylindrical screw-

threaded portion B at one end of the bar A, of the same diameter as the bar A and having on one side a single square-bottomed longitudinal groove b, and a twist-drill C at the other end of the bar A, of greater diameter than the said bar and provided with a spiral groove.

We claim—

The design for a drill-bar, as herein shown and described.

In testimony whereof we affix our signatures in presence of two witnesses.

JAMES A. GUTHRIE.
HEBER R. WILSON.

Witnesses:

G. RAYMOND JOY,
CHAS. B. PINEO.
